[57] CLAIM

The ornamental design for a room divider, as shown and described.

DESCRIPTION

FIG. 1 is a perspective view of a room divider showing our new design;

FIG. 2 is a front elevational view thereof;

FIG. 3 is a side elevational view thereof;

FIG. 4 is a top plan view thereof;

FIG. 5 is a rear elevational view thereof;

FIG. 6 is a bottom plan view thereof.

The fabric weave which is partially shown is understood to repeat uniformly throughout the circumscribed area.

FIG. 3

FIG. 4

FIG. 5

FIG. 6
